UNITED STATES PATENT OFFICE.

GEORGE VON DER HEYDE, OF MONTCLAIR, NEW JERSEY.

GOLF CLUB.

Application filed April 12, 1928. Serial No. 269,332.

This invention has reference to golf clubs, and has for its main object to provide the golf player with an emergency device in the form of an umbrella, that is carried in the 5 caddy bag with the usual assortment of golf clubs, and which is disguised by simulating a regular golf club of some form in general use.

A further object of the invention is to 10 combine a golf club, such as a putter, with an umbrella, so that the putter will have its usual operation, and then when needed, the umbrella is simply removed from the club shaft and brought into use by the player.

15 In the accompanying drawing, showing an embodiment of the invention:—

Figure 1 is perspective view.

Fig. 2 is a similar view, partly in section.

Fig. 3 shows the umbrella detached.

20 Fig. 4 shows the upper end of the shaft.

Fig. 5 shows a portion of the shaft, enlarged.

In playing the game of golf, it is not deemed in good form or sportmanlike to 25 carry a regular umbrella, in the caddy bag, or along with the player; and as the game is often played in uncertain weather, a sudden shower or hard rain is sometimes encountered when the player is some considerable distance from any form of shelter, so that the player is liable to great danger 30 to health, by being drenched before a shelter or protection from the storm can be reached, that not infrequently results in the player contracting a severe cold, or influenza or 35 even pneumonia may result.

The purpose of the present invention is to provide an umbrella that as carried has all the appearances of a regular golf club, 40 and can be carried in the customary caddy bag with the other clubs, and which when a rain comes up, can be quickly and easily brought into use to protect the player.

45 While the device may be a mere dummy club to be used simply as an umbrella, it may be combined with a regular golf club in such form as to not interfere with the normal use and function of the club. This may be most readily effected with a light 50 form of club, such as the putter, that is given a short light swing to merely roll the ball into a near by pocket or hole.

In the arrangement shown in the drawing, 55 the club comprises a shaft 5, somewhat tapering of tubular form that carries the putter head 6 at the lower end. This shaft for the

larger portion of its length from the upper open end 7, down to the portion 8, is tubular with a very thin wall, preferably of steel.

In this chambered shaft is inserted an 60 umbrella, that is specially designed to slide into such comparatively small space. As shown this comprises a stem 10, with usual ribs 12 and spreaders 13, and a cover 14, and the usual stem extension 15. These 65 parts close together in very small compact form, so that this member can be rolled up and slid into the tubular or chambered portion of the shaft. The stem extension 15 of the umbrella is received in the socket portion 70 16 of the shaft, that is given a corresponding shape, as shown.

At the upper end of the umbrella the stem 10 is rigidly and permanently secured to a head 17, in the form of a short plug adapted 75 to snugly fit into the open end 7 of the shaft 5; and this head is shown provided with a top flange 18, that will limit the movement of the head into the shaft, by engaging the edge or end of the shaft.

Suitable securing means are provided between the umbrella head and the shaft end, and as shown lugs 19 on the head 17 engage bayonet slots 20 in the edge of the shaft.

By this means the umbrella is securely 80 retained in the tubular shaft of the golf club, and the flange and head of the umbrella make the usual form of club end or top; and the extension stem 15 of the umbrella will fit snugly in the socket at 16, so that the 90 umbrella is tightly held in the shaft; and the extension 15 serves to provide the needed weight or balance for the swing of the club in use.

A club of this character resembles very 95 closely the usual putter, and will have the same qualities and functions, when the umbrella is needed, the head 17 is merely turned and drawn out to remove the umbrella from the shaft, and when a complete 100 umbrella is provided for use by the player.

What I claim is:—

1. A golf club provided with a head and a tubular shaft, and an umbrella comprising a stem with ribs spreaders and cover, which is arranged to slide into the tubular shaft, a short head secured to the upper end of the umbrella stem and having a detachable retaining engagement with the end of the tubular shaft, the shaft being provided with 105 a reduced bore at the lower portion adapted to receive the stem extension beyond the cover 110

to assist in weighting the club whereby a shoulder is provided against which the central portion of the umbrella body seats, the end of the umbrella shaft being smaller than 5 the reduced bore and shorter than said bore whereby to lie free from the walls and end of the reduced bore.

2. A golf club comprising a shaft of thin tubular form with a striking head on the 10 smaller end, and an umbrella consisting of a stem with ribs spreaders and a cover and which is arranged to slide into and out of

the said tubular shaft, the umbrella stem being provided at the free end with a short head arranged to slide partly into the upper open end of the said tubular shaft and provided with locking means to removably and rigidly hold the umbrella inside of the club and to permit the normal use of the club with the umbrella concealed therein.

Signed at New York, N. Y., this 11th day of April, 1928.

GEORGE VON DER HEYDE.
